UNITED STATES PATENT OFFICE.

EVERETT E. BUSSEY, OF MALDEN, MASSACHUSETTS, ASSIGNOR TO ALEXANDER P. BROWNE, TRUSTEE, OF CAMBRIDGE, MASSACHUSETTS.

SCREW-PROPELLER.

1,175,408.

Specification of Letters Patent.

Patented Mar. 14, 1916.

Application filed November 22, 1913. Serial No. 802,411.

To all whom it may concern:

Be it known that I, EVERETT E. BUSSEY, a citizen of the United States, and a resident of Malden, in the county of Middlesex and State of Massachusetts, have invented a new and useful Improvement in Screw-Propellers, of which the following is a specification.

My invention relates to screw propellers and its object is to improve and simplify 10 the construction thereof and increase the efficiency of the same in the manner herein-after set forth.

One embodiment of my invention is illustrated in the accompanying drawings, in which—

Figure 1 is a side elevation showing a portion of the stern of a ship with my improved propeller secured in position and Fig. 2 is a 20 vertical section.

In the particular drawings selected for more fully disclosing my invention, 1 represents the stern of the ship, to the stern-post 2 of which is secured the stuffing-box 25 3 with its packing 4 and cap 5 for the propeller shaft 6 which extends rearwardly through the stern-post and is secured in any suitable manner as by the nuts 7 to the boss 8. The boss 8 consists of the frustum of a 30 cone having a smooth unbroken exterior surface to which the blades 11 are secured, and as shown in the present instance, said blades are preferably cast integral with said frustum. A convenient means for attaching 35 the frustum to the shaft consists in providing the former with a base 8' and a centrally-disposed hub 9, through which the shouldered shaft extends and to which it is secured by the nuts 7. It will be obvious, 40 however, that various other means may be employed for attaching the frustum to the shaft. Secured to the outer end of said frustum is a cone-shaped cap 10, having a smooth unbroken surface from base to apex, 45 said cap and frustum constituting a cone having a smooth unbroken surface from its base 8' to its apex. Preferably the cap is threaded to the interior of the outer edge of the boss, said threads being cut in the opposite sense to that of the rotation of the propeller.

I prefer to interpose between the boss and the stern of the vessel a cylinder 12, the

rearward end of which preferably overlaps the forward end of the boss, and the forward end of which is secured to the stern preferably as shown in the present case by cutting a slot in the lower portion of the cylinder, so that said lower portion will straddle the stern-post, as shown at 13, and 60 passing screws or nails 15 through the flanged forward edges 14 of the cylinder into the stern.

By means of the construction above described I eliminate the drag caused by the 65 ineffective inner portions of the blades and the water-resistance caused by the base 8', the entire surface of each blade from the boss to the tip thereof being effective for propulsion and the inclosing cylinder 12 70 preventing the drag on the ship that otherwise would result from the contact of the base 8' with the water.

I am aware that heretofore attempts have been made to suppress the ineffective inner 75 ends of the blades by securing the blades to a cylindrical boss of large diameter; but I have found that such construction is ineffective in practice, whereas by means of a propeller constructed in accordance with 80 the present invention I have obtained an increase in efficiency of over thirty per cent. Such increase in efficiency is due in large part to the employment of a boss consisting of the frustum of a cone instead of a cylinder and a cone-shaped cap for said frustum, the external surface of the cone so formed being smooth and unbroken from base to apex, and also to the cylinder interposed between the stern of the vessel and the 85 base of the boss.

It will be obvious that various modifications may be made in the apparatus specifically described without departing from the principle of my invention.

I claim:

In a propeller, a boss consisting of a frustum of a cone and a base therefor, a hub arranged at right angles to said base and inclosed within said frustum, a cap so secured to said frustum as to form therewith a cone having a smooth unbroken surface from base to apex, blades secured to and extending outwardly from said boss, a shaft extending from the stern of the vessel with 100 105 which said propeller is to be used, and pass-

ing through said hub, means for attaching said hub to said shaft, and a cylinder interposed between said propeller and the stern of said vessel, said cylinder having its rearward end overlapping said boss and its forward end secured to the stern of said vessel.

In testimony whereof, I have hereunto

subscribed my name this 21st day of November, 1913.

EVERETT E. BUSSEY.
